UNITED STATES PATENT OFFICE.

ARTHUR H. SWEETLAND, DECEASED, LATE OF LOS ANGELES, CALIFORNIA, BY INEZ SWEETLAND, OF LONG BEACH, CALIFORNIA, EXECUTRIX OF SAID ARTHUR H. SWEETLAND.

CASE FOR ELECTRIC HAND DRILLS.

1,411,539.

Specification of Letters Patent. Patented Apr. 4, 1922.

Original application filed October 20, 1919, Serial No. 331,864. Divided and this application filed June 23, 1921. Serial No. 479,868.

To all whom it may concern:

- Be it known that ARTHUR H. SWEETLAND, deceased, late a citizen of the United States, and resident of Los Angeles, in the county of 5 Los Angeles and State of California, did invent new and useful Improvements in Cases for Electric Hand Drills, of which the following is a full, clear, and accurate disclosure.
- 10 The present invention pertains generally to electrically operated hand drills, and specifically to a case therefor; the particular object being to provide a case or housing of this character, which will be simple and inexpensive to manufacture; admit of ease and economy in assembling, together with the several parts of the drill; and, in its construction, will be conducive to efficient handling of the drill.
- 15 In this connection it may be stated that the drill is designed to be held and operated by one hand, other details of which are shown and described in a co-pending application, Serial No. 331,864, filed October 20th, 1919, 25 of which this case is a divisional continuation.

A more detailed description of the case will be made in the following specification, reference being made therein to the accompanying drawings, forming a part thereof, and in which—

Fig. 1 is a side elevation of the case; Fig. 2 a rear end elevation thereof; Fig. 3 a front elevation thereof; Fig. 4 a longitudinal vertical section taken through the center thereof, as indicated by the line 4—4 on Fig. 2 showing the enclosed drill mechanism in place, Fig. 5 is a transverse view taken as indicated by the line 5—5 on Fig. 4; and Fig. 40 6 is a similar view with the plate 27 removed.

In the drawings the numeral 10 designates the body portion of the case, which may be constructed of any suitable material, and 11 45 a handle or hand-grip, preferably formed integral therewith. The body portion 10 is preferably cylindrical, being designed to house an electric motor 12; one end thereof being closed by an end-wall 13, also preferably formed integral therewith; the opposite 50 end being enclosed by a removable end plate

structure, generally designated by the numeral 14.

The handle 11 is hollow, having an opening 15 extending therethrough communicating with the interior of the case; being joined to the end wall 13 of the case 10, intermediate its longitudinal axis and its periphery, and designed to extend downwardly to form a "pistol-grip" suitable for holding the drill 60 in one hand. A cable 16 is passed through the opening 15 in the handle 11, to furnish electrical energy for operating the motor 12; this cable connecting with a suitable spring switch 17, located in the end wall 13 of the 65 casing above and to one side of the handle connection, and designed to be actuated by the thumb of the hand holding the drill, through the medium of a push button 18, suitably arranged and positioned for this purpose. 70 The details of this switch need not here be explained.

One end of the shaft 19, of the armature 20 is revolvably journaled in a suitable bearing 21 in the end wall 13; the opposite end 75 being likewise journaled in a bearing 22, in the end plate structure 14, in the manner shown.

The end plate 14, in addition to providing a bearing for one end of the armature shaft 80 19, also serves as a support and partial housing for a drill chuck shaft 23, on the inner end of which a spur gear 24 is rigidly mounted. The shaft 23 is revolvably journaled in a bearing 25—preferably formed 85 integral with the plate 14—and is driven through the medium of the gear 24 meshing with a smaller gear 26, formed on the adjacent end of the armature shaft 19. The plate 14 is recessed—as at 14^a—to receive 90 the gears 24 and 26, the housing being completed by a complementary circular closure plate 27, secured to the inner face of the plate 14 by means of screws 28, as clearly shown in Figs. 4 and 5.

The closure plate 27 also serves as a thrust plate for the shaft 23, during operation of the drill; being provided, for this purpose with a thrust bearing block 29, adapted to be engaged by a ball thrust bearing 30, carried in an axial bore 30^a in the end of the shaft 23.

The end plate 14 is of the configuration clearly shown in Figs. 3, 4 and 5; the upper portion 14^b being substantially circular, concentric with the bearing 22, and of a diameter to conform to the diameter of the case 10; the lower or recessed portion 14^a being likewise substantially circular, concentric with the bearing 25, and of a diameter and depth sufficient to surround and enclose the perimeter and one side of the gear 24.

The upper portion 14^b has a substantially annular flange 31, adjacent its periphery, extending inwardly from its inner face, and adapted to fit into the case 10 to prevent lateral displacement of the former; this flange forming a shoulder 32 to abut against the end of the case in the manner shown. The flange 31 terminates at the periphery of the closure plate 27 (see Fig. 4) and the outer face of this plate is co-planar with the shoulder 32, so that an unbroken engagement is made with the end of the case 10; thereby obviating the necessity of recessing this end of the case, the advantage of which, in the present instance, will be later explained.

The plate 14 is removably secured to the case 10 by means of diametrically opposed screws 33, extending therethrough and screw-threadedly engaging internally screw-threaded bores in bosses 34 on the interior of the case (see Figs. 1 and 2). Thus the plate 14, together with the plate 27, carrying the shaft 23 and gear 24, may be removed as a unit from the case 10 to gain access to the interior thereof, merely by removing screws 33.

It may be here noted that the longitudinal axis of the shaft 23 is substantially in alignment with the line of push of the handle 11, in order that the force exerted upon the latter during the drilling operation will be in alignment with the drill bit; thereby obtaining the most efficient results. In this connection attention is directed to the fact that in case it should be desired to bore a hole in an otherwise inaccessible corner, screws 33 may be removed and the plate 14 and its carried parts rotated through 180°, and the screws replaced; the shaft 23 then extending from the side of the case 10 opposite the handle 11, or diametrically opposite the position shown in the several figures of the drawings. By reason of the outer face of the plate 27 being co-planar with shoulder 32 and the screws 33 diametrically opposed, the position of the plate 14 may be thus changed relative to the case 10; the parts fitting alike in either position.

This rotatable feature, however, need not be limited to 180°, as it may be 90°, or less, merely by providing the proper number of bosses 34.

While there is herein shown and described the preferred specific embodiment of the in-

vention, it is nevertheless to be understood that the right is reserved to make any changes or modifications in structure which properly come within the scope of the appended claims.

Having described a preferred form of the invention, I claim:

1. In an electrically driven hand drill the combination of an electric motor, a case therefor, said case comprising a body portion for housing the motor, a closure plate removably secured to one end of said body portion, the motor armature shaft being journaled at one end in said body portion and at its opposite end in said removable plate, a chuck shaft journaled in said removable plate below the armature shaft, a gear on the chuck shaft, and a gear on the armature shaft meshing with the first mentioned gear to drive the chuck shaft, the closure plate being recessed to receive said gears, and another closure plate, secured to the first mentioned closure plate, to complete the housing for the chuck shaft and gear secured thereto.

2. In an electrically driven hand drill the combination of an electric motor, a case therefor, said case comprising a body portion for housing the motor, a closure plate removably secured to one end of said body portion, the motor armature shaft being journaled at one end in said body portion and at its opposite end in said removable plate, a chuck shaft journaled in said removable plate parallel with and below the armature shaft, a gear on the chuck shaft, a gear on the armature shaft meshing with the first mentioned gear to drive the chuck shaft, the closure plate being recessed to receive and house said gears, and another closure plate secured to the first mentioned closure plate to complete the housing of the chuck shaft and gear secured thereto, the first mentioned closure plate being secured to the motor housing by diametrically opposed screws.

3. In an electrically driven hand drill the combination of an electric motor; a case therefor; said case comprising a body portion for housing the motor, a closure plate removably secured to one end of said body portion, the motor armature shaft being journaled at one end in said body portion and at its opposite end in said removable plate, a chuck shaft journaled in said removable plate parallel with and offset from the armature shaft; a gear on the chuck shaft; a gear on the armature shaft meshing with the first mentioned gear to drive the chuck shaft; the closure plate being recessed to receive and house said gears; a second closure plate secured to the first mentioned closure plate to complete the housing of the chuck shaft and gear secured thereto, the outer face of said last mentioned plate being co-planar

- with the inner face of the first mentioned plate to form an unbroken engagement with the end of said body portion; the first mentioned closure plate being secured to said body portion by diametrically opposed screws.
4. In an electrically driven hand drill the combination of an electric motor; a case therefor; said case comprising a body portion 10 for housing the motor, a closure plate removably secured to one end of said body portion, the motor armature shaft being journaled at one end in said body portion and at its opposite end in said removable plate, a chuck shaft journaled in said removable plate parallel with and offset from the armature shaft; a gear on the chuck shaft; a gear on the armature shaft meshing with the first mentioned gear to drive 15 the chuck shaft; the closure plate being recessed to receive and house said gears; a second closure plate secured to the first mentioned closure plate to complete the housing 20 of the chuck shaft and gear secured thereto, and to form a thrust bearing for the chuck shaft, the outer face of said last mentioned plate being co-planar with the inner face of the first mentioned plate to form an unbroken engagement with the end of said 25 body portion; the first mentioned closure plate being secured to said body portion by diametrically opposed screws.
5. In an electrically driven hand drill the combination of an electric motor; a case 30 therefor; said case comprising a cylindrical body portion for housing the motor; a closure plate removably secured to one end of said body portion, the motor armature shaft being journaled at one end in said body portion and at its opposite end in said removable plate, a chuck shaft journaled in said removable plate parallel with and offset from the armature shaft; a gear on the chuck shaft; a gear on the armature shaft meshing 35 with the first mentioned gear to drive the chuck shaft; the closure plate being recessed to receive and house said gears; a second closure plate secured to the first mentioned closure plate to complete the housing 40 of the chuck shaft and gear secured thereto, and to form a thrust bearing for the chuck shaft, the outer face of said last mentioned plate being co-planar with the inner face of the first mentioned plate to form an unbroken engagement with the end of said body 45 portion; the first mentioned plate having an inwardly extending flange to extend into said body portion to prevent its lateral dis-
- placement; said plate being also secured to the body portion by diametrically opposed screws.
6. In an electrically operated hand drill, the combination of an electric motor; a case therefor; a handle for supporting the case; a removable closure plate secured to one end 60 of said case; a chuck shaft carried by said plate and operatively connected to said motor; said shaft being axially offset relative to the center of the case; and means to secure said closure plate to the case so the chuck shaft may extend therefrom in diametrically opposed positions.
7. In an electrically operated hand drill, the combination of an electric motor; a case therefor; a handle extending from one end 65 of the case; a removable closure plate secured to the end of the case opposite said handle; a chuck shaft carried by said plate and operatively connected to the motor, said shaft being axially offset relative to the case; said 70 closure plate being attachable to the case so the chuck shaft will extend therefrom in either of two diametrically opposed positions.
8. In an electrically operated hand drill, the combination of an electric motor; a case 75 therefor; a handle extending radially from one end of the case; a removable closure plate secured to the opposite end of the case; a chuck shaft carried by said plate and operatively connected to the motor; said shaft being axially offset relative to the case; said 80 closure plate being attachable to the case so the chuck shaft will extend substantially axial of the point of attachment of said 85 handle or from a point diametrically opposite thereto.
9. In an electrically operated hand drill; the combination of an electric motor; a case therefor; a handle extending radially from 90 one end of the case; a closure plate removably secured to the opposite end of the case; a chuck shaft carried by said plate and operatively connected to the motor; said shaft being axially offset relative to the center of 95 the case; said closure plate being attachable to the case to permit its rotation and attachment so the chuck shaft may extend from the case in different positions relative to the handle.
- In witness that I claim the foregoing I have hereunto subscribed my name this 17th day of June, 1921.

INEZ SWEETLAND,
Executrix of Arthur H. Sweetland, deceased.
